SHINGLE GUIDE

William Leonard, Laurel Hill, Long Island, N. Y.,
assignor to George Ramsey and Frank J. Kent,
New York, N. Y.

Application February 5, 1931, Serial No. 513,519

7 Claims. (Cl. 33—188)

This invention relates to building equipment and particularly to a guide for laying shingles.

Heretofore various forms of guides have been proposed to facilitate the laying of shingles with their bottom edges in alignment and with the desired area of the shingles exposed to the weather. The devices heretofore proposed have, however, had various disadvantages as to manufacture and as to ease and convenience of use.

10 The general object of the present invention is to provide a convenient, reliable, and inexpensive guide for use in laying shingles or the like.

Another object of the invention is to provide a reliable shingle guide that can be readily 15 mounted adjacent a surface to be shingled and then used for laying a large number of courses of shingles without any change other than the shifting of a conveniently movable guide bar.

Fig. 1 is an isometric view showing the form of 20 the invention selected for illustration.

Fig. 2 is a fragmentary sectional view showing one of the standards and the means for supporting the guide bar.

Fig. 3 is a fragmentary sectional view showing 25 the supporting of the guide bar, the view being taken on the line 3—3 of Fig. 2.

Fig. 4 is a section taken on the line 4—4 of 30 Fig. 2.

Fig. 5 is an isometric view of one end of the 35 guide bar.

Fig. 6 is an isometric view showing the outer 40 end of the guide bar positioning bracket.

Standards 7, 7 are mounted parallel to each 45 other and in spaced relation to a surface 8 which is to be shingled. This may be conveniently accomplished by lower brackets 9, 9 and upper brackets 10, 10 all of which may be attached by any suitable means such as nails 11. In some instances all of the brackets 9 and 10 may be secured to the surface 8, but in other instances the lower brackets 9 may be attached to a previously laid course of shingles, as will be explained later. As shown in the drawings, brackets 9 and 10 each make pin and slot connection 50 with the standards 7 so that the distance between the standards 7 and the surface to be shingled can be varied. When the standards have been spaced at the desired distances from surface 8, they are fixedly clamped to the brackets 9 and 55 10 by winged nuts 12.

Slidably mounted on the iron standards 7, 7 are guide bar supporting brackets designated as a whole by 15. As shown more particularly in Fig. 3, the brackets 15 have sides 16, 17 and 55 18 which embrace three sides of the channel

shaped standards 7 and have projecting lugs 19, 19 which engage the edges of channels 7. Thus, the brackets 15 make a running fit with the standards and can only move lengthwise thereof. Pivoted at intervals along the standards 7 are L-shaped fingers 21 constructed as shown in Fig. 2. Under the action of gravity these L-shaped fingers 21 normally assume the positions shown in full lines in Fig. 2 and thus they constitute laterally extending projections 10 adapted to support the brackets 15. As shown in Figs. 2 and 3, each finger 21 is long enough to engage under the brackets 15 at 22.

Each bracket 15 has an outwardly extending 15 square arm 24 over which there is telescopically movable a sleeve 25 secured to the arm 24 by a pin and slot connection at 26. Projecting upwardly from the upper surface of sleeve 25 are transversely extending abutments 28 and 29 spaced a distance equal to the width of a guide 20 bar 30. On one of the brackets 15, the abutment 28 has a longitudinally extending finger 28^a for a purpose which will become apparent.

Guide bar 30 may be made from a suitable 25 piece of channel iron, and it may have one end provided with a series of notches 31. With the two brackets 15 at the same level, guide bar 30 is held in a horizontal position by the brackets 15; and it is held transversely of itself by up- 30 standing abutments 28 and 29, which engage the sides of the guide bar. In addition, the guide bar is held longitudinally of itself by finger 28^a which makes a more or less loose fit with any of the slots 31.

After a course of shingles has been laid with 35 the base of the shingles against the guide bar 30, the guide bar is moved toward the standards 7 to bring it out from beneath the bottom of the shingles. This movement of the guide bar is permitted by the sleeves 25 which are telescopically attached to the arms 24 of the brackets 15. Then the brackets 15 are slid upwardly on the standards 7 to the position for laying the next course of shingles. As a bracket engages a finger 21 from beneath, the finger is automatically folded up toward the position shown in dotted line in Fig. 2, thus permitting the bracket to pass to a position above the finger. The finger then falls by gravity into the position shown in full lines in Fig. 2 ready to support the bracket 40 45 50 55 60 65 70 75 80 85 90 95 100 105 110 115 120 125 130 135 140 145 150 155 160 the bracket 15. This facilitates moving the brackets 15 upwardly one at a time.

Lower brackets 9, 9 may be equipped as shown with guide bar retaining abutments 28' and 29' similar to abutments 28 and 29 on brackets 15. Also, one of the lower brackets 9 may have a finger 28^a similar to finger 28^a on one of the brackets 15. In laying the very first course of shingles, the guide bar 30 may be positioned by 10 the lower brackets 9 as shown in dot-dash lines in Fig. 1. In so laying the shingles, a space equal to the width of one shingle may be left at each bracket 9 and a shingle fitted into the gap after the bracket 9 has been removed. Various 15 alternative procedures for laying the first row of shingles will be apparent to those skilled in the art. For example, the very first row of shingles may be laid without the use of the present invention, using the edge of the roof, 20 or the like to aid in getting a correct alignment of the first course. Once the first course has been laid, lower brackets 9 may be attached to the surface of the laid shingles. After the area within the range of the equipment has been 25 shingled, the brackets 9 and 10 may be removed and the equipment transferred to a new area. To remove the brackets 9 and 10 it is simply necessary to unhook them from the nails 11 in an obvious manner, after which the nails may 30 be either removed or driven down.

While only two standards 7 have been shown, it is obvious that more than two may be used. In laying a long line of shingles a long guide bar 30, positioned by three or more standards 7 can be used. On the other hand, the standards may be arranged in pairs, as shown in Figs. 1 and 2, and several pairs be used side by side, each pair having its own guide bar 30.

The present invention may be embodied in 40 forms other than the one particularly disclosed, and hence the disclosure herewith is merely illustrative in compliance with the patent statutes and is not to be considered as limiting.

I claim:

- 45 1. A guide for laying shingles comprising a pair of standards; means to attach both ends of the standards to a surface to be shingled with the standards lying in a plane substantially parallel to and spaced from such surface, brackets carried by the standards, said brackets extending from the standards towards the surface to be shingled at an angle to such surface and being adjustable longitudinally of the standards; and a guide bar positioned by the brackets.
- 50 2. A guide for laying shingles comprising a pair of standards; means to attach both ends of the standards to a surface to be shingled with the standards lying in a plane substantially parallel to and spaced from such surface, brackets carried by the standards, said brackets extending
- 55

from the standards towards the surface to be shingled at an angle to such surface and being adjustable longitudinally of the standards; a guide bar positioned by the brackets; and means to prevent the guide bar from shifting transversely of the standards.

3. A guide for laying shingles comprising a pair of standards; means for attaching both ends of the standards to a surface to be shingled, said means comprising brackets which project away from said surface when mounted, said brackets having pin-and-slot connections with the standards and the pins being provided with nuts to fixedly clamp the standards to the brackets at a variable distance from the surface to be shingled; additional brackets supported on the standards, said additional brackets being adjustable longitudinally of the standards; and a guide bar positioned by said additional brackets.

4. A guide for laying shingles comprising a 20 standard; a guide bar positioning bracket slidably mounted on said standard; and a series of L-shaped detent members pivotally mounted on said standard, the L-shape providing the respective detent members with two legs, the first leg 25 normally projecting laterally in position to engage and support the bracket but being foldable in an upward direction to permit the bracket to be raised from detent to detent and the second leg normally engaging the standard to hold the 30 first leg in bracket supporting position.

5. A guide for laying shingles comprising a standard; means to mount the standard in spaced relation to a surface being shingled with the standard extending substantially perpendicular to the rows of shingles; and a guide bar positioning bracket carried by said standard, said bracket being extensible in a direction laterally of the standard and substantially perpendicularly to the surface being shingled.

6. A guide for laying shingles comprising a standard; a guide positioning bracket carried by said standard; a notched guide bar positioned by said bracket; and means projecting upwardly from said bracket, said means having a portion 45^a entering a notch in the bar and having another portion engaging the face of the bar.

7. A guide for laying shingles comprising a pair of standards; brackets for mounting the standards in spaced relation to a surface to be shingled; guide bar supporting brackets slidable on said standards; means to support said guide bar brackets at a succession of points along the standards; and a guide bar supported on the ends of said guide bar brackets, said guide bar brackets being telescopic to permit the guide bar to be withdrawn laterally from beneath a course of shingles that have been laid.

WILLIAM LEONARD. 60
